METHOD OF MAKING STITCHDOWN SHOES

Darius W. Bunker, Quincy, Mass., assignor to
United Shoe Machinery Corporation, Paterson,
N. J., a corporation of New Jersey

Application July 27, 1933, Serial No. 682,475

4 Claims. (Cl. 12—142)

This invention relates to methods for use in the manufacture of stitchdown shoes.

In the manufacture of stitchdown shoes, it is usual to secure to the bottom of the last a sole 5 the margin of which extends beyond the last bottom and is referred to as an extension sole. The upper is then assembled upon the last and its margin secured in outturned relation to the extension sole. In one method of lasting as usually 10 practised, a portion of the upper is wiped down the side of the last, forced into the angle between the side of the last and the projecting margin of the sole and secured in the angle by means of a staple driven through the upper and sole, this 15 operation being carried on progressively about the periphery of the shoe. Another usual method is to work the upper into the angle between the side of the last and the projecting margin of the sole and to secure it by a seam located in the 20 angle. More recently attempts have been made to combine these two methods by applying the staple lasting method to secure the upper in lasted relation to the sole at salient points only about the periphery of the shoe and then to sew 25 a seam through the upper and sole substantially along the line of the previously driven staples. This practice results in frequent breakage of needles since the stitches and staples are substantially in the same line.

30 Objects of this invention are to provide a method of making stitchdown shoes which will facilitate and improve their manufacture and obviate the breakage of needles. With these objects in view the invention comprises working an outturned upper, at salient points about the periphery of the shoe, over a last and against the margin of a substantially flat extension sole, securing the upper to the sole at each point by a metallic fastening, staple or other driven fastening, driven 35 through the upper and the sole extension and spaced outwardly from the angle between the side of the last and the projecting margin of the sole or, more strictly speaking, between the side of the shoe and the outturned portion of the upper, 40 and then further tensioning the upper and working it slightly under the bottom of the last while the staples remain in place preferably by utilizing end-embracing wipers which act to shape the outwardly bulging portions of the upper between 45 the staples to the sides of the last and act on the upper inwardly of the staples simultaneously to draw all parts of the toe of the upper tightly over 50 the last and to force it into the angle between the side of the last and the projecting margin of the sole and slightly under the last bottom. There-

after the upper is attached to the extension sole by a seam located in the angle formed by the wipers and between the staples and the side of the last, thus securing the upper in lasted position substantially in the position in which it was placed by the wipers. After the seam is sewed the staples may be removed if desired.

In the drawing,

Fig. 1 is a sectional view, partly in side elevation, of a shoe being operated upon by a stapling mechanism, the staple being placed outwardly of the angle between the extension sole and the side of the last;

Fig. 2 is a perspective view of the toe of a shoe after the upper has been secured to the sole at salient points around the toe of the shoe;

Fig. 3 is a sectional view illustrating a sole support and end-embracing wipers acting upon the upper inwardly of the staples to force it under the last bottom;

Fig. 4 is a perspective view illustrating the step of sewing the seam between the staples and the side of the last to secure the upper in the angle between the side of the last and the projecting margin of the sole; and

Fig. 5 is a fragmentary sectional view of a completed shoe.

In the practice of my improved method of making stitchdown shoes, a first extension sole 10 is secured by tacks or otherwise to the bottom of the last 12, and an upper 14 is assembled upon the last. The last and the projecting margin of the sole are then supported on an anvil 16 and a staple nozzle 18 is utilized to wipe the upper down the side of the last and to work it into the angle 20 between the side of the last and the projecting margin of the sole. The driver passage 22 of the nozzle 18 is spaced from the side of the last by a thickened portion 24 of the nozzle so that a staple 26 is driven in a location spaced outwardly 30 from the angle 20. A machine suitable for this operation, except for the thickened wall of the nozzle, is disclosed in Letters Patent of the United States No. 1,227,196, granted June 26, 1920, upon an application of Matthias Brock. This operation of stapling the upper to the sole is carried on at salient points about the periphery of the shoe, it being customary under most conditions to employ three staples at the toe of the shoe, one staple being placed at each side of the toe 35 near the tip line and one at the end of the toe, the points of attachment corresponding to the tack locations of the pulling-over machine; the stapling operation thus corresponds to and takes the place of the usual pulling-over operation with 40

this advantage, that, the points of attachment of the upper to the sole being located outside the line of action of the edges of the end-embracing wipers, the staples may remain in the shoe during the lasting operation and cause the tensioning effect of the wipers to be applied to that portion of the upper which extends over the last without substantial loss of the longitudinal and transverse pull applied to the upper by the action 10 of the stapling nozzle.

Preferably the toe portion of the shoe will now be operated upon in a manner disclosed diagrammatically in Fig. 3, where the sole of the shoe is supported on a table 28 which is raised relatively 15 to end-embracing wipers 30 which are arranged to advance and close about the toe of the shoe, the shoe being held down upon the table 28 by a yielding toe rest 32. With the wipers 30 engaging the upper and holding it against the sides 20 of the last, the table 28 is raised, causing the outwardly bulging portions 29 (Fig. 2) of the upper to be conformed to the shape of the last. After the table has reached the position shown, the wipers 30 close a predetermined distance to carry the fold or angle of the upper between the side 25 of the last and the projecting margin of the sole under the last bottom to a slight extent so that a definite crease will be formed by the wipers about the periphery of the toe at the location 30 where the seam uniting the upper and the sole is subsequently to be sewed. In this operation it will be seen that the upper is held by the staples 26 from inward movement with the wipers 30 and hence the wipers 30 act to draw the upper material 35 from the part of the upper which extends over the top of the last and thus increase the tightness of the lasting effect produced by the stapling operation. A machine suitably organized for carrying out this step of the method is disclosed in Letters Patent of the United States 40 No. 1,861,832, granted June 7, 1932, upon an application of W. C. Baxter.

A seam 34 is now sewed about the periphery of the shoe, at least from the breast line of the heel around the forepart to the breast line again, the seam being located in the angle between the side of the shoe and the outturned portion of the upper and between the side of the shoe and the staples 26. This operation may be performed, as 45 illustrated in Fig. 4, by means of a machine having a guide 36 to engage the side of the shoe and a straight needle 38 with mechanism to form a chainstitch. Such a machine is disclosed in Letters Patent of the United States No. 1,864,510, granted June 21, 1932, on an application of B. T. 50 Leveque. The work of this machine is greatly facilitated by the fact that the staples 26 are located out of the path of the needle so that there is no danger of the needle being broken by contact with the staples. The shoe may be completed in the usual manner by attaching an outsole 40 to the extension sole 10 and the outturned portion of the upper by a seam 42 located outwardly of the staples 26 if the staples are left in the shoe. Preferably a welt strip 44 is laid over the outturned portion of the upper and secured 55 to the shoe by the seam 42 so as to cover both the staples 26 and the seam 34.

Having thus described my invention, what I claim as new and desire to secure by Letters Patent of the United States is:

1. That improvement in methods for use in the manufacture of stitchdown shoes which consists in assembling an upper and a flat extension sole upon a last, working the upper over the last and securing the upper at spaced locations to the extension sole by fastenings driven at locations outwardly spaced from but close to the angle between the side of the last and the projecting margin of the sole, simultaneously working all portions of the upper about the toe into the angle between the side of the last and the projecting margin of the sole, and sewing a seam in said angle through the outturned margin of the upper and the extension sole between the fastenings and the side of the last. 10

2. That improvement in methods for use in the manufacture of stitchdown shoes which 20 consists in assembling an upper and a flat extension sole upon a last, working the upper over the last and securing outturned portions of the upper at spaced locations to the extension sole by fastenings driven at locations outwardly spaced from but close to the angle between the side of the shoe and the outturned portion of the upper, working the portions of the upper between the fastenings into the angle between the side of the last and the projecting margin of the 25 sole, and sewing a seam in said angle through the outturned margin of the upper and the extension sole between the fastenings and the side of the last. 30

3. That improvement in methods for use in 35 the manufacture of stitchdown shoes which consists in assembling an upper and an extension sole upon a last, working the upper over the last and securing the upper at spaced locations to the extension sole by staples driven at locations 40 outwardly spaced from but close to the side of the last and driven through the projecting margin of the sole, working all portions of the upper about the toe into the angle between the side of the last and the projecting margin of the sole so 45 that the crease extends slightly under the last bottom, and sewing a seam in said angle through the outturned margin of the upper and the extension sole between the staples and the side of the last. 50

4. That improvement in methods for use in the manufacture of stitchdown shoes which consists in assembling an upper and an extension sole upon a last, working the upper over the last in 55 outturned relation to the extension sole and securing the upper at spaced locations to the extension sole by staples driven at locations spaced outwardly from the angle between the side of the last and the projecting margin of the sole, simultaneously working the portions of the upper 60 between the staples into the angle between the side of the last and the projecting margin of the sole and under the last bottom, and sewing a seam in said angle through the outturned margin of the upper and the extension sole between the 65 staples and the side of the last.

DARIUS W. BUNKER.
